SHALLOW WELL SELF-PRIMING PUMP

Charles J. Bergh, Racine, Wis., assignor to Jacobsen Manufacturing Company, Racine, Wis.

Application March 9, 1945, Serial No. 581,876

2 Claims. (Cl. 103—5)

1

The present invention relates to what is commonly called a domestic water system, wherein an impeller or jet type pump is connected to the bottom of a pressure tank and a connection is supplied from the tank to the inlet of the pump so the water in the tank may act as a primer for the pump when the pump is first started.

An object of the present invention is to provide a unitary injector member adapted to form a simple inexpensive and efficient direct connection between the pump and tank, the connection being secured to the tank and pump by means of bolts or cap screws and gaskets, so that the connecting member may be easily machined and fitted with a jet and a venturi and easily connected to the pipe which extends into the well.

An important object of the present invention is to provide a device in three separate units for convenience in manufacturing and shipping.

Another object of the present invention is to provide an impeller pump which can be conveniently driven by an electric motor and positioned with the tank and connecting member in a convenient place which may be remote from the well and whereby a single pipe may be the driven member of the well or extend into a well casing.

Generally stated, objects of the present invention are to provide a pumping system particularly adapted for domestic use because it can be made at low cost, operated efficiently and is not apt to get out of order after constant use over a period of many years.

To these and other useful ends, my invention consists of parts, combinations of parts or their equivalents and mode of operation, as herein-after described and claimed and shown in the accompanying drawings in which:

Fig. 1 is a plan view of my complete invention, the pressure tank being cut away at its top and shown in section.

Fig. 2 is a sectional view of the pump and injector showing a fraction of the pressure tank and receiving chamber.

Fig. 3 is a bottom view of the injector unit.

Fig. 4 is a bottom view of the pump, illustrating a fraction of the injector unit.

Fig. 5 is an outlet end view of the injector unit.

Fig. 6 is a vertical section of the receiving chamber.

Fig. 7 is a top view of the receiving chamber.

A detailed view of member G is illustrated in Figures 1 and 2 in my copending application, Serial #580,650, filed March 2, 1945, Air charger for jet pumps, which resulted in Patent 2,421,237, May 27, 1947.

As thus illustrated the motor in its entirety is designated by reference character A, the motor supporting pedestal by reference character B; and the pump in its entirety is designated by ref-

2

erence character C; the injector unit is designated in its entirety by reference character D; the pressure tank by reference character E; and the receiving chamber by reference character F. I provide an air charger and a pressure controller for the motor, these members are designated in their entireties by reference characters G and H, respectively.

The pump comprises a housing 10 which is preferably generally circular in horizontal cross section having at its top a centrally positioned well 11, the upper end of the well being machine trued as at 12—12, the bottom being shaped as at 13 and having an opening 14 which is machine trued and extending into a horizontal inlet opening 15. Surrounding chamber 11 and near the bottom thereof, I provide an annular chamber 16 which is connected with chamber 11 by a narrow annular slit 17. This chamber starts from nothing as at or near 18 and gradually increases in size as indicated by an arrow and as shown in Figure 4 and finally terminates in an outwardly directed outlet as at 19.

I provide an impeller 30, the lower end of which may be rotatably mounted in opening 14 and arranged to rotatably clear 13 as at 31. Member 30 has an inlet opening 32 and a diameter as at 33, which is slightly less than the diameter of opening 12. Inlet 32 suitably merges into a narrow annular slit 34, which registers with member 17 and is slightly narrower than member 17; thus when opening 15 is supplied with water and the pump is operated, the water will by centrifugal force be discharged in chamber 16 through slit 34. When member 30 is driven at the proper speed in the direction indicated by arrow in Fig. 4, a considerable pressure will be generated in outlet 19 because of the shape of member 30 and chamber 16.

Member 30 is secured to the lower end of a shaft 40 which is rotatably mounted in cap 41 which is secured to member 10. Cap 41 is provided with a motor supporting extension 42 and a stuffing box 43 is provided through which shaft 40 extends so if there is water pressure in chamber 11, it will not leak out around the shaft. Shaft 40 is operatively connected to motor A.

Injector member D forms operating connections between receiving chamber F and pump C and is designed and also secured to tank E as follows:

Member D is provided with a duct 45 which forms a connection between receiving chamber F and the inlet duct 46 of pump C. I provide a chamber 47 in member D, which registers with pump outlet 19.

Chamber 47 is provided with a partition 48, having a threaded opening as at 49. A duct 50 is formed in the top of member D terminating in an outlet as at 51. A small chamber 52 is formed by means of a partition 53 having a threaded open-

ing 54 in alignment with threaded opening 49. A nozzle 60 is adapted to be screw threaded into 49 and is shaped as illustrated in Figure 2. A Venturi tube 61 is screw-threaded into 54. Member 61 is shaped as illustrated, its outlet 62 being somewhat larger than its inlet end, the inlet end being curved outwardly forming an annular opening around the outlet end of nozzle 60, the nozzle terminating as at 63 with a suitable size opening so when water is discharged from the opening into member 61 a partial vacuum will be formed in chamber 52.

I provide screw-threaded openings 64—64 which extend into opposite sides of chamber 52. One of these openings may be closed with a pipe plug, the other being suitably connected to inlet pipe 65, which leads to the driven well pipe or the pipe which extends into the well through a driven casting. It will be noted that duct 45 is provided with a drain plug 66 and that duct 50 is provided with a connection 67, which is operatively connected to the motor controlling switch H. Member G is operatively connected to pressure tank E at its top and at about the general water level in the tank and to chamber 52 by means of a tube 68. The operation of members G and H will hereinafter appear.

Chamber 50 is preferably supplied with a screw-threaded opening 69 to which a pressure gauge 70 may be connected for indicating the pressure tank pressure as will hereinafter appear.

I will now describe units E and F. Tank E is open at the bottom as at 80 and closed at its top (not shown) and having a partition 81 forming a closure for the tank. Member 81 is shaped as shown in Figure 1 so as to give it strength to resist pressure in the tank. The receiving chamber F is provided with a flanged opening 82, which registers with duct 45. Duct 45 and opening 82 are adapted to receive the Venturi tube 61 as illustrated in Figure 2. Flange 83 extends freely through an opening 84 in the side wall of tank E. Member D is supplied with flanges 86—86, each flange being suitably reinforced and secured to flanges 83 and 85 by means of bolts 87—87 and gaskets 88—88. Receiving chamber F is provided with flanges 91—91 which rest against the inside wall of tank E and are secured thereto by means of bolts 92; thus when member D is secured to members C and F and member F is secured to member E a firmly held together assembly will be provided.

Tank E is adapted to rest on a plank floor or a concrete foundation; in either event the weight of members A, B and C may be made to rest on the tank support by means of a pair of legs 95, having screw-threaded into their bottoms, cap screws 96 with a suitable locking nut. Member F is relatively small and preferably cast iron or cast steel having a duct 97 which registers at one end with opening 51 of duct 50. The inner end of duct 97 is provided with a fitting 98 which is suitably secured to member 81 as illustrated in Figure 1 so as to provide a passageway from duct 50 to the pressure tank. Fitting 98 is provided with a relatively small opening whereby when the pump is started enough pressure is provided for operating the venturi and thereby create enough vacuum in chamber 52 to draw water from the well.

It will be seen because of the fact that the receiving chamber F is relatively small and member E is opened at the bottom, plenty of room is supplied for securing member F to the wall of the

7 tank and for securing fitting 98 to pressure tank bottom 81.

By scrutinizing the various features it will be seen that the injector will draw water from the inlet pipe 65 and force it into the receiving chamber F through the Venturi tube 61, that the water discharged into member F will flow into the suction inlet of pump C through ducts 15 and 45 and that the surplus water will be discharged into the pressure tank through ducts 50 and 97, that all of the space within receiving chamber F, the injector and the pump will at all times be kept full of water because of the connection of ducts 97, 50 and 47 to the pressure tank. Therefore immediately the pump reaches operating speed the injector will act to draw water from the well, the surplus pumped being discharged into the pressure tank.

Thus member H being connected to duct 50 20 will cause the motor to operate when the pressure in the pressure tank falls below or raises above a predetermined pressure. The operation of member G is too well known to require detailed description. For the present it may be stated that 25 since member G is operatively connected to chamber 52, it will be operated by the vacuum in this chamber. A valve in member G is adapted to be opened when the water in this member reaches a predetermined height caused by the water in the pressure tank flowing into member G when above its connection to the tank and whereby when the water level in member G falls below a predetermined point the valve will be closed.

It will be seen that applicant has provided a 30 simple, efficient, automatic economic domestic pumping unit for shallow wells, which will at all times be self priming.

Clearly many minor detail changes may be made in the design shown without departing from 35 the spirit and scope in my invention as recited in the appended claims.

Having thus shown and described my invention I claim:

1. In a self priming device of the character described, comprising an impeller pump having driving means therefor, a pressure tank having its bottom closure a distance from the bottom of the wall of the tank forming an open chamber, a relatively small receiving chamber in said open chamber, an injector forming an operating connection between said pump and receiving chamber, a passageway from said receiving chamber to the inlet of said pump and a passageway 45 from the outlet of said pump to said tank, said injector having a receiving chamber adapted to be connected to a well and being associated with the nozzle of said injector, the bottom of said tank being positioned above the pump and its inlet and outlet connections, whereby the connections and pump will at all times be supplied with 50 water from the tank for priming purposes and whereby when the pump has reached an operating speed, water will be discharged conjointly into the receiving chamber and pressure tank, said receiving chamber extending freely through an opening in the wall of the pressure tank, the injector forming a rigid connection between the pump and receiving chamber, said receiving chamber having surfaces adapted to contact the 55 wall of the tank on opposite sides of the opening therein and being rigidly secured to the wall.

2. A self priming device of the character described, comprising an impeller pump having driving means therefor, an injector unit detachably connected to the outlet and inlet side of

said pump by means of flat gasketed surfaces and bolts, a pressure tank having its bottom closure positioned a distance above the bottom of the wall of the tank forming an open chamber having an opening in its wall, a relatively small receiving chamber having a flat surface which registers with said opening and being detachably secured to the other end of said injector unit by means of a gasket and bolts, said receiving chamber having a detachable flanged connection to the inside of said open chamber adjacent said opening, said injector unit having a connection from the outlet of the pump to the nozzle of the injector and a duct which leads therefrom to another duct in the top of said receiving chamber, said other duct having a detachable connection into the bottom closure of said pressure tank and near the center thereof, an injector suction chamber through which the injector nozzle extends and having an

inlet connection adapted to be connected to a well pipe and a venturi adjacent the outlet end of said nozzle having an outlet into said receiving chamber, a duct in said injector unit leading from the receiving chamber to the inlet of said pump.
